(57) **CLAIM**

The ornamental design for a space needle lamp, as shown and described.

DESCRIPTION

FIG. 1 is a perspective view of a space needle lamp according to our new design;

FIG. 2 is a right orthogonal elevation view thereof, the left side orthogonal view being a mirror image;

FIG. 3 is a front orthogonal elevation view thereof;

FIG. 4 is a rear orthogonal elevation view thereof;

FIG. 5 is a top plan view thereof;

FIG. 6 is a sectional view as indicated in FIG. 3;

FIG. 7 is a perspective view of a second embodiment of a space needle lamp according to our new design;

FIG. 8 is a right orthogonal elevation view thereof, the left side orthogonal view being a mirror image;

FIG. 9 is a front orthogonal elevation view thereof;

FIG. 10 is a rear orthogonal elevation view thereof;

FIG. 11 is a top plan view thereof;

FIG. 12 is a sectional view as indicated in FIG. 9;

FIG. 13 is a perspective view of a third embodiment of a space needle lamp according to our new design;

FIG. 14 is a front orthogonal elevation view thereof, the rear, left and right side orthogonal views being identical;

FIG. 15 is an elevation view thereof shown rotated 45 degrees with respect to FIG. 14;

FIG. 16 is a top plan view thereof; and,

FIG. 17 is a sectional view as indicated in FIG. 14.
